(No Model.)

C. H. MEYLAN.
REPEATING WATCH.

No. 390,501.

Patented Oct. 2, 1888.

UNITED STATES PATENT OFFICE.

CHARLES H. MEYLAN, OF NEW YORK, N. Y.

REPEATING-WATCH.

SPECIFICATION forming part of Letters Patent No. 390,501, dated October 2, 1888.

Application filed April 10, 1888. Serial No. 270,170. (No model.)

To all whom it may concern:

Be it known that I, CHARLES H. MEYLAN, of the city and State of New York, have invented an Improvement in Repeating and Striking Watches, of which the following is a specification.

Watches have heretofore been made in which there is a sonorous body that is struck by a hammer for denoting the hour of day, and by subsequent strokes the minutes, one stroke being struck for each five minutes. Mechanism for accomplishing this object is represented in the application, Serial No. 241,690, of Henri Onesime Stauffer, filed June 18, 1887. My present invention is an improvement upon this device, whereby the parts are so arranged that they can be introduced into watches of ordinary construction, or nearly so.

In my improvements the stem-winding mechanism corresponds to that which has heretofore been used, and the particular levers and hammers for striking the wire or sonorous body resemble those in the aforesaid application; but I introduce the snail-wheel, which determines the number of strokes, one for each five minutes, upon the minute-hand arbor and between the pinion made use of in setting the hands and the wheel and tubular arbor upon which the hour-hand is placed. Thereby I am enabled to make use of wheels for reducing the speed from the minute-hand arbor to the hour-hand arbor, similar to those usually employed in ordinary watches, and the arrangement of parts is such that much less space is required between the watch-plate and dial for the parts of the repeating mechanism than if the minute-snail were placed below the setting-pinion.

In the drawings, Figure 1 is a plan view, in larger size, of one plate of the watch and of the gearing connected therewith. Fig. 2 is a section, in still larger size, at the line $x-x$, Fig. 1. Fig. 3 is a detached view of one of the racks made use of in partially winding up the spring-barrel for giving motion to the striking mechanism, and Fig. 4 is a detached view of the ratchet-wheel that acts upon the hammer-cam in striking the hours. Fig. 5 is a detached view of the minute-snail and its surprise, the star-wheel upon the arbor of the hour-snail, and a part of the finger that acts upon the minute-snail, the parts being in the

position they assume as the hour is completed.

The spring-barrel is represented at D by dotted lines as between the two plates of the watch, and the plate B, which is represented in Fig. 1, is recessed in its surface to receive the respective wheels and levers, hereinafter described, and there is a stem, 3, passing through a bearing and provided with a pinion, 4, gearing into a wheel, 15, and the axis of this wheel 15 forms a pivot upon which the lever C can be rocked, and there is a pinion, 7, constantly in gear with the wheel 15 and having its pivot upon the lever C. In the normal position of the parts this pinion 7 is in gear with the teeth upon the spring-barrel D, and when in this position the spring-barrel is wound by rotating the stem 3 by the crown-wheel, as usual. The push-piece 9 is provided for swinging the lever C in one direction, so as to separate the pinion 7 and the wheel of the spring-barrel D when it is desired to set the hands, and there is a spring, 1, that acts against the lever C to bring the pinion 7 into contact with the teeth upon the spring-barrel when the parts are not otherwise acted upon.

At the other end of the lever C is a gear-wheel, 8, constantly in gear with the wheel 15, and when the push-piece 9 is moved the lever C is swung so that the pinion 8 is brought into gear with the intermediate pinion, b, and this in turn rotates the second wheel, b', that is in gear with the pinion d upon the arbor d', so as to rotate this arbor d' and the minute-hand d' for setting the same, and the reducing-gears e, e', and e'' are similar to those made use of in ordinary watches, except that the tubular arbor e', that connects the pinion e' to the wheel e, is sufficiently long for affording the proper space between the pinion d and the wheel e' upon the arbor d' for the snail and surprise, as hereinafter described. It will be noticed upon reference to Fig. 2 that the pinion d of the central arbor, d', gears directly with the gear-wheel e, and that the pinion e' thereof gears directly with the wheel e' upon the tubular arbor o' for the hour-hand o'. The sizes of these wheels and pinions d e' e'' are such that the tubular arbor o' receives one revolution for each twelve revolutions of the arbor d' and minute-hand d'.

The train of gearing that extends from the spring barrel to the escapement and balance wheel of the watch is to be of any desired character, and is not represented herein, except that at 5 I have represented a portion of the tubular arbor or center cannon in the train of gearing for the arbor d' , and this arbor d' is revolved by frictional contact with the tubular or cannon arbor f , so that the arbor d' may 10 turn within the tubular cannon or arbor f in setting the watch; but the friction of the parts will always be sufficient for turning the hands and also the mechanism that controls the action of the repeating or striking mechanism.

15 The portion of the arbor d' which is within the tubular arbor f is larger than that portion of the arbor d' that passes through the cannon f , so that a shoulder can be formed thereon at 20 p , for the reception of the minute-hand snail T , which snail is to be riveted or firmly secured at this point to the arbor d' . The separate plate 50, known as the "surprise," has a hole through it for the passage of the arbor d' , and such surprise is loose upon said arbor d' ; 25 but it is kept in place by the pinion d , which pinion d is driven on a slightly-tapering portion of the arbor d' so tightly that it will not turn upon said arbor when the hands are being set. The surprise is carried around with the minute-snail T by a pin, 52, upon the latter, which pin is within a slot or notched portion in the surprise, and which slot allows a limited motion to the surprise, and upon the surprise is a pin, 51, that acts upon the star-wheel 35 30 and moves the same one tooth each hour, and upon the arbor of the star-wheel 35 is the hour-snail 36. The minute-snail T is made with twelve steps, as usual—one step for each five minutes, and the step that is 35 farthest from the arbor d' of said snail is partially cut away to allow the finger 41 to pass to the step that is nearest to said arbor d' . Just before the hour is completed the pin 51 acts upon a tooth of 35, and as said wheel 35 40 is turned it forces the inclined portion of the spring 53 out from between the two teeth it had been bearing against, and exactly as the hour is completed the pin 51 passes by the tooth of 35 it had been pressing against and 45 the spring 53 slips past the tooth of 35 that had been moving it and passes in behind said tooth and completes the movement of the star-wheel 35. At the same time the tooth of the star-wheel next following the one that had 50 been acted upon by the pin 51 strikes said pin 51 and moves the surprise the amount limited by the notch therein to the position shown in Fig. 5, so that a portion, 54, of the surprise forms a continuation of the step of the minute-snail 55 T that is farthest from the arbor d' , and such portion 54 prevents the finger 41 passing to the step of the snail nearest to the arbor d' if said finger is acted upon immediately after the hour is passed. The finger 41 is upon a lever provided with a segmental rack, V , hereinafter described, and if this lever is actuated and the finger 41 brought into contact with the first

step of the snail, or the surprise that forms part of this first step, during the first five minutes of the hour no blow will be given by the minute-hammer, because said first step prevents the finger 41 being moved a sufficient distance; but as soon as it is five minutes past the hour then the snail T will have been revolved, so that its second step T will be in such a position 75 that if the finger 41 is brought against said second step one blow will be struck by the minute-hammer to indicate five minutes past the hour, and so on for the successive steps of the snail T . After the hour is completed the surprise remains stationary until the snail T in its revolution has brought the pin 52 against the surprise in the opposite end of the slot in said surprise. Then the snail T and surprise move together.

80 The toothed segment U is upon the pivot 39, and upon the same pivot is a swinging lever, Q , that is acted upon by a push-piece, I , so as to swing such lever Q and toothed segment U by moving the push-piece I in the direction of the arrow. There is also a lever, Q' , upon said pivot 39, and this lever Q' has a finger, 37. By moving the push-piece I the segment U is acted upon and the teeth thereof rotate the pinion 30 and arbor 16 to wind up the 90 volute spring that is connected to this arbor 16, and the amount of motion that can be given to this toothed segment U depends upon the position of the hour-snail 36, because the lever Q' is moved by the portion q' of said toothed 95 segment U taking against the lever Q' , and the movement of U and Q' continues until the finger 37 comes into contact with one of the segmental faces of the said hour-snail 36. A pin, i' , upon the toothed segment U , which 100 pin is shown by dotted lines in Fig. 1, moves said lever Q' and its finger 37 in the other direction.

105 Upon the arbor 16 is a segmental ratchet, S , and there is a stud, 24, and swinging escapement 23, with a tooth, 25, that is acted upon by the teeth of the segmental ratchet S to move the hammer and strike the bell, as in the aforesaid application. When the push piece I is moved in the direction of the arrow, and the pinion 30 and segmental ratchet S are revolved as far as the hour-snail 36 will permit, as many 110 teeth of the segmental ratchet S pass by the tooth 25 as there are hours to be struck. The escapement 23 yields under the action of the 115 spring 65 as the teeth of S pass by the tooth 25 of said escapement during the forward movement of the segmental ratchet S ; but the motion given to said escapement is not sufficient for the hammer t' to strike the bell. 120 During the return movement of the segmental ratchet S the teeth of S give said escapement a greater movement, and one blow of the hammer t' is given for each tooth of S that 125 passes by the tooth 25 of the escapement 23. While this segmental ratchet S is revolving back to its normal position the pinion 30 restores the toothed segment U and the parts therewith connected to their normal positions, 130

and the spring 38 aids in these movements by acting upon the lever Q. There is also a toothed rack, V, upon the pivot 40, which acts upon the second escapement, 42, to strike the five-minute blows upon the bell or alarm, as in the aforesaid application, and the spring 45 moves this toothed rack V in one direction, and the arm t upon the arbor 16 acts to move this toothed rack V in the other direction, and 5 there is a spring-pawl, l, the end of which catches in a small notch at one end of the toothed rack V, as seen in Fig. 1, and upon the spring-pawl l is a cam-surface, l', and the parts are so placed that when the toothed 10 segment U is moved by the push-piece I, as before described, the pawl l upon this toothed segment U comes in contact with the cam portion l' of the spring-pawl l, and this disconnects the end of the pawl from the toothed 15 rack V, and the spring 45 swings this toothed rack V, so that the teeth of such rack V pass by the second escapement, 42, and this movement continues until the finger 41 upon this toothed rack V is arrested by coming into contact with one of the segmental surfaces upon 20 the minute snail-wheel T, and the parts stand in this position during the time that the segmental ratchet S is being moved past the escapement 23. The finger t is loose upon the 25 arbor 16, and upon said finger is a pin, 75, that is in the path of an offset upon said arbor 16.

The finger t remains stationary while the arbor 16 and its toothed segment S are being 30 rotated in one direction, and it also remains stationary during the return movement of said arbor and segment while the hours are being struck, and continues stationary during the said return movement until the offset 35 comes in contact with the pin 75. Then said finger t turns with the arbor 16 and moves said toothed rack V back against the action of the spring 45, and the teeth of V act against the escapement 42 and strike the five-minute 40 strokes. The number of these strokes will depend upon the distance that the toothed rack V has been swang by the spring 45 before the finger 41 has come into contact with the minute snail-wheel T. It is therefore to be understood 45 that this snail-wheel T will occupy such a position to the minute-hand d², that is connected therewith, that but one tooth of the rack V will pass by the second escapement, 42, if the minute-hand is between five and ten minutes, two teeth if it is between ten and fifteen minutes, and three teeth if it is between fifteen and twenty minutes, and so on.

By placing the pinion d of the minute hand

adjacent to the watch-plate and raising the wheel e' of the hour-hand, and placing the 60 minute-snail T and its surprise between them, and arranging the gearing as shown, I am enabled to obtain the necessary space for the various parts of the repeating mechanism, and this additional space required is about one-third less than that required if the parts were arranged with the minute-pinion above the snail T. If desired, the minute-snail may be increased in size and be of a shape adapted for minutes instead of periods of five minutes. 65

The sonorous wires are shown by dotted lines at t', Fig. 1, and the hammers t' l', for striking the five-minute and hour blows, respectively, are also shown by dotted lines in said Fig. 1. 70

I do not claim, broadly, the combination of a pinion upon the arbor of the minute-hand, a wheel upon the tubular arbor of the hour-hand, and an intermediate wheel and pinion gearing with the first-named pinion and wheel, 80 respectively; but

I claim as my invention—

1. The combination, with the striking mechanism in a repeating-watch, of the arbor d' and pinion d on the same, the gearing e, e', and 85 e', and the tubular arbor o', for the hour-hand o', and the minute-snail T, and surprise upon the arbor d' and between the wheels e e', substantially as set forth.

2. The combination, with the winding-stem, 90 the swinging plate C, and pinion S, of the pinion d upon the arbor d' and the intermediate gear-wheels, b b', the wheel e, gearing into the pinion d, the pinion e', wheel e', tubular arbor o', and hour-hand o', and the minute-hand snail 95 T, fastened upon the arbor d' and adjacent to the pinion d, substantially as set forth.

3. The minute snail-wheel T and arbor d', to which the same is fastened, the pinion d upon the same arbor, and the gearing to the hour-hand, in combination with the escapements for striking, the toothed segment U, toothed rack V, the pusher I and lever Q, for moving the toothed segment U, and segmental ratchet S, the spring-pawl l, for holding the toothed rack V, 105 the pawl i, for unlatching the spring-pawl l, and the finger t upon the arbor 16 of the segmental ratchet S, for returning the toothed rack V to its normal position, substantially as set forth.

Signed by me this 23d day of March, 1888.

C. H. MEYLAN.
